FLUID ACTUATED PRESS

Reginald C. Howard, 11924 Montana Ave., Apt. 5, Los Angeles, Calif., and Lawrence W. McDowell, Jr., 4223 Patrice Road, Newport Beach, Calif.
Filed May 11, 1964, Ser. No. 366,439
10 Claims. (Cl. 100—257)

The present invention relates to a fluid actuated press, and more particularly to a press which is actuated by an expandible, unarticulated container or bag.

A conventional press includes a stationary bed, a plurality of vertical guide posts fixed at their lower extremities to the bed, and a ram which is vertically slidably mounted on the posts and defines a die set or working area with the bed. In many applications it is important that the mechanism or agency which actuates the ram toward the bed to perform the working operation be immediately and sensitively responsive to the control system. Sensitivity of response is very important where a repetitive operation is involved, such as in the case of work operations that require several hundred ram strokes per minute, and where the forming operation must be accomplished in accordance with a precise and predetermined time-pressure cycle. Most hydraulically operated presses of the prior art characteristically possess an undesirable lag in ram response subsequent to initiation of hydraulic fluid flow into the actuating mechanism. Presses utilizing inflatable bellows to effect ram movement also are characterized by a lag in ram operation, primarily because in the collapsed state of the bellows there is an internal space which must first be filled with pressurized fluid during each cycle before the bellows can be internally pressurized to the level sufficient to drive the ram.

Accordingly, it is an object of the present invention to provide a fluid actuated press which is sensitively responsive to the agency or medium of actuation whereby a lag between movement of the ram subsequent to operation of the actuating medium is substantially eliminated and precise time-pressure cycles of operation are afforded.

Another object of the invention is to provide an improved actuator for use with a press having a die set assembly which includes a stationary bed, a plurality of vertical guide posts fixed at their lower extremities to the bed, and a ram vertically slidably mounted on the posts and defining a die set area with the bed, the actuator being adapted for mounting adjacent the upper extremities of the guide posts for actuation of the ram toward the press bed, and further adapted to be quickly and easily removed from the die set assembly for use with an identical die set assembly. In this manner, one actuator may be used with a plurality of different die set assemblies. Ordinarily, a certain amount of "set-up" time and adjustment is required to precisely locate a set of dies between the ram and press bed. However, with the arrangement just described a number of die set assemblies, each including a different die set, can be stored for production of a variety of parts at a moment's notice. All that need be done is to mount the actuator to the particular die set assembly desired. In most cases, the cost of the ram, press bed and vertical posts stored with each die set is considerably less than the labor cost which would be required to set up the dies each time in a conventional press.

Another object of the invention is to utilize an actuator which includes a flexible, unarticulated bag for actuation of the ram of the above-described die set assembly, the bag being made of a material having an elastic characteristic of longitudinal expansion without significant lateral expansion upon introduction of pressurized fluid into the bag. In a completely collapsed state, the bag is substantially absent any fluid. However, introduction of even a small amount of fluid into the bag effects a cor-

2

responding movement of the ram. Accordingly, the ram is sensitively responsive to any introduction of pressurized fluid into the bag whereby, for example, a precise time-pressure cycle may be followed and close control is afforded over a work operation requiring rapid, relatively short strokes of the ram, and all without expensive control equipment.

Another object of the invention is the provision of an actuator for a press of the above-described character which is relatively simple to operate, inexpensive to manufacture, and characterized by an extended service life.

Other objects and features of the invention will become apparent from consideration of the following description taken in connection with the accompanying drawings, in which:

FIG. 1 is a perspective view of a fluid actuated press incorporating an actuator according to the present invention;

FIG. 2 is a view taken along the line 2—2 of FIG. 1;

FIG. 3 is an enlarged detail view of the encircled area designated by the numeral 3 in FIG. 2;

FIG. 4 is an enlarged detail view taken along the line 4—4 of FIG. 2;

FIG. 5 is an enlarged detail view taken along the line 5—5 of FIG. 1;

FIG. 6 is a view taken along the line 6—6 of FIG. 5; and

FIG. 7 is a view taken along the line 7—7 of FIG. 5.

Referring now to the drawings, there is illustrated a press having a die set assembly 10 which includes a stationary press bed 12; a plurality of vertical guide posts 14 fixed at their lower extremities to the bed 12; a ram 16 vertically slidably mounted on the guide posts 14 and defining a working or die set area 18 with the press bed 12; and an actuator 20 operative to effect movement of the ram 16 toward and away from the press bed 12.

The actuator 20 includes, generally, a thrust plate 22 mounted to the guide posts 14 adjacent the upper extremities thereof; a flexible, unarticulated bag 24 to effect movement of the ram 16 toward the press bed 12 upon introduction of pressurized fluid into the bag; and fluid pressure and control apparatus 26 for introducing fluid under pressure into the bag 24.

The die set assembly 10 is a relatively inexpensive structure in which the press bed 12 is preferably rectangular in configuration, horizontally oriented, and forged or cast to provide a relatively thin supporting wall 28 defining the lower boundary of the die set area 18. The lower die of the usual die set (not shown) is attached to the upper surface of the wall 28 by any suitable means, as will be readily apparent to those skilled in the art. The supporting wall 28 is suitably reinforced by the provision of integral reinforcing ribs 30 in the underside thereof, and the four corners of the rectangular supporting wall are heavier in cross-section and each includes a vertically oriented bore 32 to receive the lower extremity of one of the four guide posts 14. Each such lower extremity includes an annular groove in which is mounted a usual snap ring 34 of a diameter larger than that of the bore 32 and received within a counter bore 36 coaxial with the bore 32. The snap rings 34 transfer to the press bed 12 the tensile forces to which the guide posts 14 are subjected during operation of the press.

The ram 16 is substantially rectangular in configuration and horizontally oriented in coplanar, coextensive relationship to the press bed 12. Its lower surface defines the upper boundary of the die set area 18, and the upper die of the usual die set (not shown) is secured to this surface in the same manner that the lower die was secured to the press bed 12.

The ram 16 is fabricated like the press bed 12, being provided with a horizontally oriented supporting wall

38 strengthened by integral stiffeners or ribs 40. The four corners of the ram 16 are of heavier cross-section and each includes a bore 42 which slidably receives the shank of a guide bushing 44. The lower extremity of the guide bushing is provided with an integral headed portion which engages the underside of the wall 38, and the upper extremity of the guide bushing is threaded for receiving a nut 46 to secure the bushing 44 to the wall 38. This arrangement permits the guide bushings 44 to be removed when they become worn, without having to replace the whole ram 16.

A flat or planar plate 48 rests upon the upper edges of the ram ribs 40 and constitutes the lower one of the reaction surfaces against which the bag 24 acts.

The thrust plate 22 is substantially rectangular in configuration, horizontally oriented, and characterized by a flat, planar lower surface constituting the upper reaction surface against which the bag 24 acts. The plate 22 includes reinforcing ribs or webs 50 radiating from a central boss 52 to the four corners of the thrust plate 22. The four corners of the thrust plate 22 are heavier in cross-section than the main portion of the plate and are each provided with a vertical bore 54 which vertically slidably receives one of the guide posts 14. This permits the thrust plate 22 to be vertically moved for adjustment and removal. Any desired vertical position of the thrust plate is maintained by pairs of split collars 56 and 58 mounted upon diagonally opposite pairs of the guide posts 14, respectively.

As best illustrated in FIGS. 5 through 7, each collar 56 includes a vertical slit or split 60 extending through the wall to the interior of the central bore thereof. A horizontal set screw 62 is threadably carried by the collar 56, rotation of the set screw 62 in one direction tending to widen the split by urging apart the opposing faces defining the split 60. This also opens up the central bore and permits the collar to be vertically slidably moved upon the associated guide post 14. Conversely, rotation of the set screw 62 in the opposite direction releases the bias force tending to open the central bore, and the split 60 narrows and the collar 56 tightly grips the guide post 14, serving as a stop past which the thrust plate cannot move.

The construction of the collar 58 is identical to the construction of the collar 56 thus far described. However, each collar 56 is additionally provided with a horizontal slot or slit 64 through all but a relatively small portion 66 of the area of the collar, as best viewed in FIG. 7. A vertical bolt 68 having an enlarged head portion is received within a complementary bore and counterbore provided in the corner of the thrust plate 22 adjacent the particular collar 56, and the upper extremity of the bolt 68 is threaded for disposition within a threaded vertical opening provided in the collar 56 in communication with the slit 64. With this arrangement, the collars 56 are adapted to grip the pair of associated, diagonally opposite guide posts 14 and suspend the thrust plate 22 in position and constrain it against downward slidable movement.

The flexible bag 24 normally assumes a flat, pancake-like configuration between the thrust plate 22 and the ram 16, and is made of a material such as rubber or the like, reinforced or otherwise, and having an elastic characteristic of longitudinal expansion without significant lateral expansion upon introduction of pressurized fluid into the bag. Such bags are commercially available. The bag 24 conforms to the bounding surfaces with which it is engaged, and is squeezed flat without any appreciable volume of air therein when the thrust plate 22 and ram 16 are closely adjacent each other. However, as will be seen, the introduction of any appreciable amount of air or other fluid immediately effects a corresponding movement of the ram 16. In this regard, hydraulic fluid may be used to expand the bag 24, but pressurized air is preferred.

As best illustrated in FIGS. 2 and 3, the bag 24 includes a central opening 70 having tapering margins which are

5 adhesively secured to a complementally tapered annular fitting 72. The fitting 72 includes an annular, horizontally and radially inwardly oriented groove 74 which snugly receives a radial flange 76 forming a part of a cylindrical split collar 78.

The collar 78 is adapted to be vertically slidably mounted upon an elongated vertical bushing 80 which is mounted within the central bore of the boss 52. The bushing 80 includes an annular groove at its lower extremity which receives a sealing element or O-ring 82, which bears against the adjacent surface of the collar 78 and provides a fluid-tight relationship therebetween. The upper extremity of the bushing 80 is provided with an integral cap 84 which overlies the upper end of the boss 52 and is provided with openings in alignment with threaded openings provided in the boss 52. A pair of machine screws 86 are disposed in these openings to securely mount the bushing 80 in position upon the boss 52 of the thrust plate 22.

20 The upper extremity of the bushing 80 is internally threaded to receive the threaded lower extremity of a conduit 88. The threaded upper extremity of the conduit 88 is connected to a usual and conventional air valve assembly 90 and, as will be more particularly described hereinafter, carries high pressure air from the assembly 90 to the interior of the bag 24 to drive or urge the ram 16 downwardly toward the press bed 12.

25 Although various means will immediately suggest themselves to those skilled in the art for effecting upward movement or return of the ram 16 after a working stroke, in the present invention this is preferably accomplished by a plurality of ram return assemblies 91 which, as best viewed in FIG. 4, are each constituted of an elongated element or rod 92 whose lower extremity is threadably mounted within a complementally threaded socket 94 provided in the ram 16. The upper extremity of each rod 92 mounts a stop element or washer 96, a nut 98, and a lock nut 100, and a biasing element or compression spring 102 is mounted upon the rod 92 with its opposite extremities bearing against the thrust plate 22 and the washer 96, respectively. The rods 92 are vertically slidably disposed through suitable openings 104 provided in the thrust plate 22 so that the ram 16 is resiliently supported by the relatively stationary thrust plate 22, but is downwardly movable against the bias of the springs 102 during a working stroke. Upon evacuation of air from the interior of the bag 24, the bias of the springs 102 effects a return or upward movement of the ram 16, as will be apparent.

30 The precise nature of the fluid pressure and control apparatus 26 associated with the thrust plate 22 and the bag 24 will vary somewhat according to the application for which the press is to be used. In the present embodiment, the apparatus 26 is adapted to operate the press in such a manner that the ram 16 is driven through a relatively short stroke of two to three inches at a rate of approximately 450 strokes per minute, although this may be adjusted within certain limits as desired. Accordingly, the particular apparatus 26 illustrated includes a usual air supply valve 106 adapted to be connected to a suitable air pump or the like (not shown), a conventional pressure gauge 108 being associated therewith to determine air pressure in the line. The outlet side of the valve 106 is connected to a usual accumulator tank 110, and from the accumulator 110 the pressurized air is carried to the valve assembly 90.

35 The valve assembly 90 is a conventional quick operating, solenoid-actuated type, responsive to electrical actuation to admit air to the bag 24 in one position and exhaust air from the bag 24 in a different position. The exhaust air passes through an exhaust conduit 112 and then through an exhaust muffler 114 to atmosphere. The apparatus for electrically controlling the air valve assembly 90 includes any one of several commercially available 40 solenoid assemblies 116 operative to effect rapid open-

ing and closing of the air valve 90 at a rapid rate. The power for energizing the solenoid assembly 116 is controlled by any suitable electrical switch 118 connected by an electrical conduit 120 to a source of power (not shown).

In operation, the actuator 20 comprising the thrust plate 22, the collars 56 and 58, the bag 24, the fluid pressure and control apparatus 26, and the ram return assemblies 91, are associated with the die set assembly 10 by slidably fitting the collars 56 and 58 and the thrust plate 22 over the guide posts 14. The lower extremities of the rods 92 of the ram return assemblies 91 are next threadably secured to the ram 16 at the desired height above the press bed 12. The collars 56 and 58 are then operated to grip the guide posts 14, as previously described. This arrangement has the important advantage of permitting a wide variation in adjustment of the shut die height, limited only by the height of the particular guide posts 14 utilized.

The power and air are next supplied by operating the switch 118 and supply valve 106, respectively, whereupon air is introduced into and exhausted from the bag 24 according to the control of the solenoid assembly 116, as will be apparent to those skilled in the art.

Upon introduction of pressurized air into the bag 24, the ram 16 is driven toward the press bed 12. The ram 16 constitutes the principal moving component and undergoes a movement corresponding to each increment of air introduced into the bag. Moreover, substantially the same pressure is applied to the ram 16, substantially evenly over the surface thereof, at each position of the ram throughout its working stroke. There is substantially no control lag or "backlash" and extreme accuracy is afforded. In addition, maintenance of substantially uniform pressure in the bag 24 over a finite period of time results in constant ram pressure over a corresponding period of time, whether this be at the end or at an intermediate point of the working stroke. This is important for certain applications in which metals must be formed according to a precisely correlated relationship of time versus pressure.

The actuator 20 can be relatively quickly, vertically slidably removed from the die set assembly 10 by demounting the rods 92 from the ram 16 and operating the collars 56 and 58 into their release positions. The actuator can then be associated with other die set assemblies of comparable dimensions whereby a number of such die set assemblies can be stored for use at a moment's notice without also having to store the more expensive actuators 20 as well.

Various modifications and changes may be made with regard to the foregoing detailed description without departing from the spirit of the invention or the scope of the following claims.

We claim:

1. In a press having a stationary bed, a plurality of vertical guide posts fixed at their lower extremities to said bed, and a ram vertically slidably mounted on and directly connected to said posts and defining a die set area with said bed, an actuator for urging said ram toward said bed, said actuator comprising:

a thrust plate mounted to said posts above said ram; means operative to maintain said thrust plate in fixed position upon said posts;

a flexible, unarticulated bag resting upon said ram and connected to said thrust plate, the material of said bag having an elastic characteristic of longitudinal expansion without significant lateral expansion upon introduction of pressurized fluid into said bag;

and means for introducing fluid under pressure into said bag whereby said ram is urged toward said bed.

2. In a press having a stationary bed, a plurality of vertical guide posts fixed at their lower extremities to said bed, and a ram vertically slidably mounted on and directly connected to said posts and defining a die set

area with said bed, an actuator for urging said cam toward said bed, said actuator comprising:

a thrust plate mounted to said posts adjacent the upper extremities thereof;

5 split collars including threaded elements operative to bias said collars and open said splits for vertically slidably mounting said collars upon said posts, and further operative to relax said bias whereby said collars clamp about said posts to maintain said thrust plate in fixed position upon said posts;

a flexible, unarticulated bag interposed between said ram and said thrust plate, the material of said bag having an elastic characteristic of longitudinal expansion without significant lateral expansion upon introduction of pressurized fluid into said bag;

and means for introducing fluid under pressure into said bag whereby said ram is urged toward said bed.

3. In a press having a die set assembly including a stationary bed, a plurality of vertical guide posts fixed at their lower extremities to said bed, and a ram vertically slidably mounted on and directly connected to said posts and defining a die set area with said bed, an actuator for urging said ram toward said bed, said actuator comprising:

25 a thrust plate mounted to said posts adjacent the upper extremities thereof and having an opening therethrough;

a flexible, unarticulated bag interposed between said ram and said thrust plate, the material of said bag having an elastic characteristic of longitudinal expansion without significant lateral expansion upon introduction of pressurized fluid into said bag, said bag including an opening and means securing said bag to said thrust plate with said opening in communication with said opening in said thrust plate; fluid pressure means including a conduit secured to said thrust plate in communication with said opening thereof for introducing fluid under pressure into said bag whereby said ram is urged toward said bed; and clamp means operative to maintain said thrust plate in fixed position upon said posts, said clamp means being further operative to permit said thrust plate and said bag to be vertically slidably removed from said posts for disassociation of said actuator from said die set assembly whereby said actuator may be quickly associated with another, identical die set assembly.

4. In a press having a stationary bed, a plurality of vertical guide posts fixed at their lower extremities to said bed, and a ram vertically slidably mounted on and directly connected to said posts and defining a die set area with said bed, an actuator for urging said ram toward said bed, said actuator comprising:

50 a thrust plate mounted to said posts above said ram; means operative to maintain said thrust plate in fixed position upon said posts;

a flexible, unarticulated bag resting upon said ram and connected to said thrust plate, the material of said bag having an elastic characteristic of longitudinal expansion for urging said ram toward said bed without significant lateral expansion of said bag upon introduction of pressurized fluid into said bag; means for introducing fluid under pressure into said bag whereby said ram is urged toward said bed; and ram return means operative upon said ram and tending to urge said ram away from said bed.

5. In a press having a stationary bed, a plurality of vertical guide posts fixed at their lower extremities to said bed, and a ram vertically slidably mounted on and directly connected to said posts and defining a die set area with said bed, an actuator for urging said ram toward said bed, said actuator comprising:

65 a thrust plate mounted to said posts above said ram; means operative to maintain said thrust plate in fixed position upon said posts;

a flexible, unarticulated bag resting upon said ram and connected to said thrust plate, the material of said bag having an elastic characteristic of longitudinal expansion for urging said ram toward said bed without significant lateral expansion of said bag upon introduction of pressurized fluid into said bag; means for introducing fluid under pressure into said bag whereby said ram is urged toward said bed; and ram return means including a plurality of elongated elements vertically slidably disposed through said thrust plate, secured at their lower extremities to said ram, and mounting stop elements at their upper extremities, said ram return means further including elongated bias means mounted upon said elongated elements and engageable at their opposite extremities with said thrust plate and said stop elements for urging said ram away from said bed.

6. In a press having a stationary bed, a plurality of vertical guide posts fixed at their lower extremities to said bed, and a ram vertically slidably mounted on and directly connected to said posts and defining a die set area with said bed, an actuator for urging said ram toward said bed, said actuator comprising:

a thrust plate mounted to said posts adjacent the upper extremities thereof; split collars including threaded elements operative to bias said collars and open said splits for vertically slidably mounting said collars upon said posts, and further operative to relax said bias whereby said collars clamp about said posts to maintain said thrust plate in fixed position upon said posts; a flexible, unarticulated bag interposed between said ram and said thrust plate, the material of said bag having an elastic characteristic of longitudinal expansion without significant lateral expansion upon introduction of pressurized fluid into said bag; means for introducing fluid under pressure into said bag whereby said ram is urged toward said bed; and ram return means operative upon said ram and tending to urge said ram away from said bed.

7. In a press having a die set assembly including a stationary bed, a plurality of vertical guide posts fixed at their lower extremities to said bed, and a ram vertically slidably mounted on and directly connected to said posts and defining a die set area with said bed, an actuator for urging said ram toward said bed, said actuator comprising:

a thrust plate mounted to said posts adjacent the upper extremities thereof and having an opening therethrough; a flexible, unarticulated bag interposed between said ram and said thrust plate, the material of said bag having an elastic characteristic of longitudinal expansion without significant lateral expansion upon introduction of pressurized fluid into said bag, said bag including an opening and means securing said bag to said thrust plate with said opening in communication with said opening in said thrust plate; fluid pressure means including a conduit secured to said thrust plate in communication with said opening thereof for introducing fluid under pressure into said bag whereby said ram is urged toward said bed; clamp means operative to maintain said thrust plate in fixed position upon said posts, said clamp means being further operative to permit said thrust plate and said bag to be vertically slidably removed from said posts for disassociation of said actuator from said die set assembly whereby said actuator may be quickly associated with another, identical die set assembly;

and ram return means including a plurality of elongated elements vertically slidably disposed through said thrust plate, secured at their lower extremities to said ram, and mounting stop elements at their upper extremities, said ram return means further including

elongated bias means mounted upon said elongated elements and engageable at their opposite extremities with said thrust plate and said stop elements for urging said ram away from said bed.

8. In a press having a die set assembly including a stationary bed, a plurality of vertical guide posts fixed at their lower extremities to said bed, and a ram vertically slidably mounted on and directly connected to said posts and defining a die set area with said bed, an actuator for urging said ram toward said bed, said actuator comprising:

a thrust plate mounted to said posts adjacent the upper extremities thereof and having an opening therethrough;

split collars including threaded elements operative to bias said collars and open said splits for vertically slidably mounting said collars upon said posts, and further operative to relax said bias whereby said collars clamp about said posts to maintain said thrust plate in fixed position upon said posts;

a flexible, unarticulated bag interposed between said ram and said thrust plate, the material of said bag having an elastic characteristic of longitudinal expansion without significant lateral expansion upon introduction of pressurized fluid into said bag, said bag including an opening and means securing said bag to said thrust plate with said opening in communication with said opening in said thrust plate; fluid pressure means including a conduit secured to said thrust plate in communication with said opening thereof for introducing fluid under pressure into said bag whereby said ram is urged toward said bed; and clamp means operative to maintain said thrust plate in fixed position upon said posts, said clamp means being further operative to permit said thrust plate and said bag to be vertically slidably removed from said posts for disassociation of said actuator from said die set assembly whereby said actuator may be quickly associated with another, identical die set assembly.

9. In a press having a die set assembly including a stationary, substantially rectangular bed, four vertical guide posts fixed at their lower extremities adjacent the four corners of said bed, and a substantially rectangular ram vertically slidably mounted on and directly connected to said posts and defining a die set area with said bed, an actuator vertically slidably demountable from said die set assembly and adapted to urge said ram toward said bed, said actuator comprising:

a substantially rectangular thrust plate mounted to said posts adjacent the upper extremities thereof and having an opening therethrough;

a flexible, unarticulated bag interposed between said ram and said thrust plate, the material of said bag having an elastic characteristic of longitudinal expansion without significant lateral expansion upon introduction of pressurized fluid into said bag, said bag including an opening and means securing said bag to said thrust plate with said opening in communication with said opening in said thrust plate; fluid pressure means including a conduit secured to said thrust plate in communication with said opening thereof for introducing fluid under pressure into said bag whereby said ram is urged toward said bed; and split collars secured to said thrust plate and including threaded elements operative to bias said collars and open said splits for vertically slidably mounting said collars upon at least a pair of said posts, and further operative to relax said bias whereby said collars clamp about said posts to maintain said thrust plate in fixed position upon said posts.

10. In a press having a die set assembly including a stationary bed, a plurality of vertical guide posts fixed at their lower extremities to said bed, and a ram verti-

cally slidably mounted on and directly connected to said posts and defining a die set area with said bed, an actuator for urging said ram toward said bed, said actuator comprising:

- a thrust plate mounted to said posts adjacent the upper 5 extremities thereof and having an opening there-through;
- a flexible, unarticulated bag interposed between said ram and said thrust plate, the material of said bag having an elastic characteristic of longitudinal expansion without significant lateral expansion upon introduction of pressurized fluid into said bag, said bag including an opening and means securing said bag to said thrust plate with said opening in communication with said opening in said thrust plate; 15
- fluid pressure means including a conduit secured to said thrust plate in communication with said opening thereof for introducing fluid under pressure into said bag whereby said ram is urged toward said bed;
- ram return means resiliently suspending said ram from 20 said thrust plate and tending to resist movement of said ram toward said bed and bias said ram away from said bed;
- and at least a pair of split collars secured to said thrust plate and including threaded elements operative to 25 bias said collars and open said splits for vertically slidably mounting said collars upon said posts to

adjust the height of said ram above said bed and to permit complete removal of said actuator from said die set assembly, and further operative to relax said bias whereby said collars clamp about said posts to maintain said thrust plate in fixed position upon said posts.
